UNITED STATES PATENT OFFICE.

CHARLES S. BURTON, OF OAK PARK, ILLINOIS.

CONTAINER FOR MUSIC ROLLS AND THE LIKE.

Application filed October 4, 1921. Serial No. 505,377.

To all whom it may concern:

Be it known that I, CHARLES S. BURTON, a citizen of the United States, having residence in Oak Park, in the county of Cook 5 and State of Illinois, have invented certain new and useful Improvements in Containers for Music Rolls and the like, of which the following is a specification, reference being had to the accompanying drawings, forming 10 a part thereof.

The purpose of this invention is to provide an improved container for such articles as a perforated music roll, and specifically to provide such a container of tubular 15 form having an open end and a telescoping closure for that end. It consists in the elements and features of construction shown and described as indicated in the claims.

In the drawings:—

20 Figure 1 is a longitudinal vertical section of a device embodying this invention, the same being shown at closed position with the roll therein.

Figure 2 is a horizontal longitudinal section of the same.

Figure 3 is a perspective dissected view of a portion of the main body or tubular member at the open end with the reinforce and the closure withdrawn.

30 Figure 4 is a vertical axial section of the same device showing the closure directly withdrawn in full line and withdrawn and pivoted down to completely open position in dotted line.

35 Figure 5 is a vertical axial section of a modified form at closed position.

Figure 6 is a similar view showing the closure withdrawn but not tilted down for completely opening the container.

40 Figure 7 is a view similar to Figure 6 but with the closure tilted down to fully open position.

Figure 8 is a section at the line, 8—8, on Figure 5 with the roll removed.

45 Figure 9 is a view showing a pile of the containers, two of them being broken away and shown in vertical section at the lower forward corner, illustrating the operation for withdrawing a container from the pile 50 and for withdrawing the closure to open the container without withdrawing the latter from the pile.

Figure 10 is a dissected perspective view of the open end portion of the tubular body 55 and the reinforce and closure withdrawn,

the latter being partly broken away as shown in vertical section at the lower side.

Figure 11 is a section at the line, 11—11, on Figure 10.

Figure 12 is a perspective view of the 60 spring catch member and a withdrawal lug secured thereto.

In the form of the device shown in Figures 1, 2, 3 and 4, the box, 1, which is tubular with one end closed and the other 65 end open, is provided with a metal reinforce, 2, fitted into the open end. The purpose and effect of this reinforce is to obviate the defect which is generally recognized as constituting an objection to telescoping containers for the purpose, that objection being that such containers by reason of having an open end, that is, lacking the stiffening in transverse plane which would be afforded by such an end, are extremely liable to damage in handling when the telescoping closure, 4, is withdrawn and the tubular member is empty; and also that when these containers are assembled in a pile, the weight 70 of the pile upon the lower containers, tending to pinch the telescoping closure in the open end of the tubular box member, makes it difficult to withdraw the closure for opening the box to get access to the roll; and when the closure is withdrawn, the weight 75 of the pile tends to sway the box laterally at the open end, making it difficult to reinsert the closure as well as tending rapidly to deteriorate the box itself. The reinforce, 80

2, is therefore designed to be of sufficient 85 length, and to be made of sheet metal sufficiently heavy, to render the open end of the box substantially as stiff and as resistant to distortion as it would be made by having the end closed. In the form 90 shown in the first four figures, said metal reinforce may be a short section of square tubing dimensioned for fitting tightly within the open end of the tubular box member,

1. In practice the metal reinforce is very 100 effectively secured to the tubular box member by a little glue applied to each of the four sides for inserting the reinforce into the open end of the tubular box member. In practice it is also found that it is not 105 necessary to use actual tubing, but that a simple strip of metal of proper gauge folded up into tubular form, the ends lapped at one of the corners of the box and secured by glue applied on the outside adjacent these 110

meeting ends makes a thoroughly effective reinforce. In the structure illustrated advantage is taken of this reinforce as a means of securing a check-and-hinge strap, 3, to limit the withdrawal of the closure, 4, to the proper point for tilting down over the edge of the bottom side of the tubular member at the open end as illustrated in Figure 4. The closure, 4, has three sides and one end being open at the fourth side and the other end. The check-and-hinge strap is preferably a piece of fabric which is inserted through the tubular reinforce member and has the end folded down around the inner edge of the lower side thereof, as seen in Figure 3, preferably having a little glue applied securing the under-folded end to the reinforce before the reinforce is inserted into the open end of the tubular box member. The other end of the check-and-hinge strap is secured to the inner surface of the bottom side of the closure, the latter being first thrust into the reinforce, as seen in Figure 3, so far as to bring the forward edge of the bottom side of said closure into touch with the outer edge of the bottom side of the reinforce as seen in said Figure 3; and the check strap being then secured as stated to the bottom side of the closure, the limit of withdrawal of the closure from the reinforce is as fixed at the proper point for permitting the closure to tilt down over the edge of the reinforce to open position; in which action the check strap serves as a hinge.

For the purpose of withdrawing the roll from the box by the withdrawing movement of the closure, so that the end of the roll may be protruding sufficiently to be taken hold of when the closure is withdrawn and tilted down to the open position, there is provided on the bottom side of the closure an abutment, 6, formed sloping on the inner side, that is, toward the cavity of the tubular box member, for entering under the end flange of the roll in the closing movement of the closure, and having an abruptly vertical shoulder on the side facing the direction of the opening movement, for positively engaging the inner face of the roll flange to withdraw it as stated. This abutment may be a wooden block triangular in cross section, extending across the width of the bottom side of the closure and covered by the secured end of the check strap, both the block and the check strap being secured by gluing to the bottom side of the closure.

For securing the closure at closed position and providing for its withdrawal, co-operating catch members are provided on the closure and on the tubular member respectively. On the closure there is mounted secured to the bottom side thereof, spring catch member, 12, secured at its inner end by clinching it around the inner edge of

said bottom side of the closure as seen at 12^a. The free end of the catch extends out along the inner surface of the bottom side of the closure to a point just behind the end of closure, the end of the catch member is bent upwardly at 12^b, and just back of the bend there is struck down from the catch a tooth, 10^c, which protrudes through an aperture, 4^a, made in the bottom corner of the closure and is of sufficient length to engage an aperture, 2^a, made in the lower side of the reinforce, just forward of which, preferably, the lower side of the reinforce is struck upward as seen at 2^b, so as to make the forward edge of the aperture, 2^a, afford a more effective engagement with the tooth, 10^c, than would be afforded by the thickness of the reinforce itself. The up-turned end, 12^a, of the catch has the corners clinched over the ends of a flexible lug, 13, which may be made of cord looped and having both ends engaged under the reflexed corners, 12^b, of the lug, the loop extending out through the aperture made by striking down the tooth, 10^c, and thence out through the said corner aperture, 4^a, of the closure. This corner aperture is extended vertically in the forward end of the closure a short distance providing a slot in which the flexible lug moves when the lug is pulled upward for disengaging the tooth, 10^c, from the aperture, 2^a, of the reinforce. Upon consideration of this catch device, it will be seen that the direct forward pull upon the lug, 12, does not disengage the catch, and that therefore the lug may be utilized by giving it a direct forward pull for withdrawing the entire container from a pile in which it may be situated, as seen in Figure 9. But if it is desired not to withdraw the container from the pile but merely to withdraw the closure from the container for getting access to the roll, the lug may be given an upward and forward pull, which will disengage the catch and then withdraw the closure to the limit permitted by the check strap, whereupon the closure being tilted down as seen in Figure 2, the end of the roll which is withdrawn a short distance by engagement of the abutment, 6, with the roll flange, may be taken hold of and withdrawn over the depressed forward end of the closure.

In the form shown in Figures 5, 6, 7 and 8, instead of locating the reinforce at the extreme forward end of the tubular box member, it is located a distance back from that end equal to the distance to which the closure is to be withdrawn in opening, and in this form the check strap, 3, engaging the bottom side of the reinforce at the rear or inner edge of the latter, is attached so as to emerge from that engagement at the outer or forward edge of the reinforce, as seen most clearly in Figure 5, which illustrates

that with this construction the slack of the check strap is looped up from said forward edge of the reinforce under the roll when the closure is closed. In either form,—that 5 is, with the reinforce in either position,—the reinforce may be made as shown in Figures 5, 6 and 7, of a strip of metal folded in tubular form with one end lapped upon the other at one side, which is preferably, as 10 shown in these figures, at the lower side, which permits the engagement of the check strap between these two laps for greater security of the engagement, the end of the check strap being also folded around under 15 the lower of the two lapped parts between the same and the lower part of the box member, as seen in Figures 5, 6 and 7. An advantage of folding the strap between the lower lapped end of the reinforce and the 20 bottom side of the box member is that strong adhesion of the glue can be obtained with the fabric. In this form, the reinforce not being present at the proper place for engagement of the catch to secure the closure in 25 closed position, means for such engagement directly with the tubular box member is provided by inserting an eyelet in the lower side of the box member at proper distance back from the open end as seen at 20.

30 I claim:—

1. In combination with a tubular box having one end open for inserting and withdrawing its contents, an interior tubular reinforce proximate to the open end; a telescoping closure sliding in said reinforce for opening and closing the box and means engaging the closure to the reinforce for limiting the withdrawal of the closure. 35
 2. In combination with a tubular box having an open end for inserting and withdrawing the contents; an interior tubular reinforce proximate to the open end; a telescoping closure sliding in said reinforce for opening and closing the box and a flexible 40 connection between the closure and the reinforce dimensioned to afford slack at closed position sufficient to permit the withdrawal of the closure to a position where it may be tilted down for the withdrawal of the contents; whereby such flexible connection constitutes a hinge between the tubular box and the telescoping closure. 45
 3. In the construction defined in claim 1, foregoing, the box being dimensioned and adapted for containing a music roll and the like; means for withdrawing the closure, and an abutment mounted on the closure for engaging the end flange of the contained roll, the withdrawing means being attached to 50 the roll-flange-engaging abutment; whereby the closure-withdrawing pull operates directly on the abutment for withdrawing the roll.

4. In combination with a tubular box having one end open for inserting and with- 55

drawing its contents; a telescoping closure sliding in the tubular box for opening and closing the same; means for limiting the withdrawal of the closure; a spring catch mounted on the inner side of the bottom 70 of the closure having a tooth projecting through an opening in said bottom, the lower side of the box being provided with a co-operating catch feature, and a flexible lug attached to the free end of the spring catch 75 extending out through the lower corner of the closure having a short vertical slot extending up from said corner to accommodate a lifting movement of the lug; whereby direct outward pull upon the lug draws 80 the entire container bodily by the engagement of the closure with the tubular body, and an upward pull on the lug disengages the latch, permitting the withdrawal of the closure from said tubular member. 85

5. In the construction defined in claim 1, foregoing, a spring catch mounted on the inner side of the bottom of the closure having a tooth projecting through an opening in said bottom, the reinforce having co-operating catch member, and a flexible lug attached to the free end of the spring catch 90 extending out through the lower corner of the closure, the front end of the latter having a short vertical slot extending upwardly 95 from said corner to accommodate a lifting movement of the lug; whereby direct outward pull upon the lug causes the spring catch to positively engage the reinforce and thereby the tubular body for drawing the 100 entire container bodily, and an upward pull upon the lug disengages the catch, permitting the withdrawal of the closure from the tubular body.

6. In the construction defined in claim 1, foregoing, the means engaging the closure to the reinforce being flexible and being engaged under the lower side of the reinforce between the same and the lower side of the body, whereby said flexible connection means 110 is folded around an edge of the reinforce at one of the limits of the sliding movement of the closure for closing and opening the box.

7. In the construction defined in claim 1, foregoing, the means engaging the closure reinforce being a flexible check strap, said strap being engaged between the lower side of the reinforce and the adjacent side of the box and emerging from the inner end of the 120 reinforce; whereby the check strap is folded around said edge of the reinforce for checking a withdrawal of the closure.

8. A music roll container, comprising an exterior tubular member closed at one end 125 and a telescoping closure for the other end, said other end having an interior tubular reinforce, and a check hinge for the closure consisting of flexible strip having one end engaged under the lower side of the rein- 130

force and emerging from said engagement at an edge of the reinforce which is at a distance back from the mouth of the tubular member such that the slack of the check strip at closed position of the closure is substantially equal to the withdrawal of the closure which brings the inner edge of the bottom thereof to the edge of the mouth of the tube member; whereby the check strip becomes a hinge for permitting the closure to tilt downward at open position.

9. A tubular box having an open end, a

tubular metal reinforce open at both ends, fitted and secured within the open end of the tubular box and a telescoping closure 15 for the end of the box, said closure being open outwardly at its said inner end and fitted for telescoping through the metal reinforce.

In testimony whereof, I have hereunto set 20 my hand at Chicago, Illinois, this 1st day of Sept., 1921.

CHARLES S. BURTON
